CLAIM

The ornamental design for a dispensing container, substantially as shown and described.

DESCRIPTION

FIG. 1 is a perspective view of a dispensing container showing my new design; the view includes a perspective view of a slice of bread onto which peanut butter is being dispensed;

FIG. 2 is a side perspective view of the dispenser; the view includes a view of a cap member that is complementally formed with respect the discharge spout of the dispenser;

FIG. 3 is a top plan view of the dispenser with the cap removed;

FIG. 4 is a bottom plan view thereof; and

FIG. 5 is a top plan view of the cap taken along line 5—5 of FIG. 2.
